UNITED STATES PATENT OFFICE.

FRANK LIPAR, OF TROMMALD, MINNESOTA.

CUSPIDOR.

1,366,267.

Specification of Letters Patent. Patented Jan. 18, 1921.

Application filed July 27, 1920. Serial No. 399,285.

To all whom it may concern:

Be it known that I, FRANK LIPAR, a citizen of Jugo-Slavia, residing at Trommald, in the county of Crow Wing and State of 5 Minnesota, have invented certain new and useful Improvements in Cuspidors, of which the following is a specification.

This invention relates to certain new and useful improvements in cuspidors and has 10 for its primary object to provide a closure valve or gate for the lower end of the funnel-shaped mouth of the cuspidor whereby the device is maintained in a closed condition to prevent the escape of odors there- 15 from and also for various sanitary purposes.

A further object of the invention is to provide a resiliently mounted closure gate for the lower end of the receiving funnel of a cuspidor, the gate being foot operated to 20 open the same when the cuspidor is used and automatically closed upon a release of pressure thereon.

With the above and other objects in view, the present invention consists in the novel 25 form, combination and arrangement of parts hereinafter more fully described in connection with the accompanying drawing and in which like reference characters indicate similar parts throughout the several 30 views.

In the drawings,

Figure 1 is a vertical sectional view of a cuspidor constructed in accordance with the present invention, the resiliently mounted 35 closure gate for the receiving funnel being shown by dotted lines in open position,

Fig. 2 is a top plan view thereof, and

Fig. 3 is a side elevational view showing the slotted guide for the gate opening 40 mechanism.

Briefly described, the invention aims to provide a sanitary cuspidor wherein the contents of the same are sealed to the atmosphere, there being provided a manually 45 operated gate at the lower end of the funnel-shaped cuspidor, that normally assumes a closed position, the same being opened by a foot lever or pedal when used and automatically closed when pressure is removed 50 therefrom, there being provided a chain connection between the pedal and resiliently mounted closure gate with a guiding sheave journaled in the side wall of the cuspidor.

Referring more in detail to the accompanying drawing and particularly to Figs. 1 and 2, there is illustrated a cuspidor of

cylindrical formation embodying a side wall 4 and a flat bottom 5 which carries a lateral foot 6 having nail receiving openings 7 therein by which foot the cuspidor is secured to a convenient support as a floor or bracket.

The cover for the cuspidor embodies an annular flange 8 inclosing the upper end of the side wall 4 and having a bayonet slot 9 opening at the lower edge thereof and received on the pin 10 carried by the wall 4, thus to lock the cover to the wall. The flange 8 of the cover carries the funnel-shaped member 11 overlying the open upper end of the cuspidor and provided with an enlarged central opening 12 shown more clearly in Fig. 2.

A resiliently mounted closure gate is adapted for closing the opening 12 and includes a disk 13 having a peripheral flange 75 14 fixed to the pin 15 journaled in the brackets 16 carried by the cover part 11. To place the closure gate 13 under tension, the rod 17 journaled in the brackets 16 has the coil spring 18 wound thereon with one free 80 end 18' engaging the underside of the cover section 11 while the other end 18'' engages the underside of the closure gate 13 as clearly shown in Fig. 1, thereby placing the closure gate under tension and operating to 85 hold the gate in a normally closed position.

To effect the opening of the gate, foot operating mechanism is associated therewith and includes the mounting of a sheave 19 in an opening 20 provided in the cuspidor wall 90 4 and from which sheave a chain 21 travels, the inner end of the chain carrying a hook 22 engaging an angle arm 23 secured to the underside of the gate 13 while the end of the chain projecting outwardly of the cuspidor 95 is attached to a foot operated lever. The foot operated lever includes an angle arm formed of a vertical leg 24 to the upper end of which the chain 21 is connected, the leg 24 being guided in its vertically sliding 100 movements by the U-shaped guide 25 having a forward vertical slot 26 through which the lower end of the leg 24 freely projects and terminates in a pedal 27.

Assuming that the gate 13 is in the closed 105 position shown in Fig. 1 with the pedal 27 elevated as illustrated by full lines, pressure on the pedal will move the chain 21 to open the gate 13 against the tension of the spring 18, the vertical sliding movements of the 110 pedal 27 being guided by the lever section 24 sliding the guide 25. When pressure is

relieved on the pedal 27, the spring 18 will return the gate 13 to its closed position, thereby practically sealing the contents of the cuspidor for sanitary and sundry purposes.

While there is herein shown and described the preferred embodiments of the invention, it is nevertheless to be understood that minor changes may be made therein without departing from the spirit and scope of the invention as claimed.

What is claimed as new is:

A cuspidor of the type described comprising a receptacle, a funnel-shaped cover therefor, a closure gate for the lower end of the funnel-shaped cover, a pair of brackets carried by said cover, a pin journaled in said brackets for supporting the closure gate, a rod journaled in said brackets, a wire

spring coiled on said rod with one end engaging the lower face of the closure gate and the other end engaging the underside of the cover to hold the gate in a normally closed position, a sheave journaled in the side wall of the receptacle and extending exteriorly thereof, a slotted vertical guide secured to the outer wall of the receptacle adjacent the bottom thereof, an L-shaped lever having the vertical leg thereof slideable in said guide and the horizontal leg projecting outwardly therefrom, a chain connection between the upper end of the leg and said gate passing over the sheave, a bracket carried by the lower edge of the receptacle for rigidly mounting the same.

In testimony whereof I affix my signature.

FRANK LIPAR.
